(57) **CLAIM**

The ornamental design for the pitcher with carrying handle, as shown and described.

DESCRIPTION

FIG. 1 is an isometric view of a pitcher with carrying handle in accordance with our new design, with the carrying handle being pivotable and shown in a pivotably extended or upright position for carrying the pitcher; FIG. 2 is a front elevation view of the pitcher with carrying handle shown in FIG. 1;

FIG. 3 is a rear elevation view of the pitcher with carrying handle shown in FIG. 1;

FIG. 4 is a left side elevation view of the pitcher with carrying handle shown in FIG. 1;

FIG. 5 is a right side elevation view of the pitcher with carrying handle shown in FIG. 1;

FIG. 6 is a top plan view of the pitcher with carrying handle shown in FIG. 1;

FIG. 7 is a bottom plan view of the pitcher with carrying handle shown in FIG. 1;

FIG. 8 is another isometric view of the pitcher with carrying handle in accordance with our new design, shown with the carrying handle in its pivotably retracted or down position;

FIG. 9 is a front elevation view of the pitcher with carrying handle shown in FIG. 8;

FIG. 10 is a rear elevation view of the pitcher with carrying handle shown in FIG. 8;

FIG. 11 is a left side elevation view of the pitcher with carrying handle shown in FIG. 8;

FIG. 12 is a right side elevation view of the pitcher with carrying handle shown in FIG. 8;

FIG. 13 is a top plan view of the pitcher with carrying handle shown in FIG. 8; and,

FIG. 14 is a bottom plan view of the pitcher with carrying handle shown in FIG. 8.

The broken lines in the various figures are directed to unclaimed portions of the pitcher with carrying handle and form no part of the claimed design.
